UNITED STATES PATENT OFFICE

JOHN RALPH HOGE AND LEONARD D. SOUBIER, OF TOLEDO, OHIO, ASSIGNEES TO
AMERICAN PATENTS CORPORATION, A CORPORATION OF OHIO

GAME APPARATUS

Application filed January 14, 1930. Serial No. 420,772.

The present invention relates to improvements in game apparatus and more particularly to means for supporting golf balls or like game pieces in position to be driven toward a target.

An object of the invention is the provision of a tee which may be repeatedly used for an exceptionally great length of time without breakage or distortion.

Another object is a provision of a tee which will automatically resume a predetermined ball supporting position after each "drive" and thereby avoid the necessity for replacing tees repeatedly.

Another object is the provision of a tee which under pressure of a golf club or the like, will quickly move out of the path of travel of the club and then automatically return to its former position.

It is also an object to provide a teeing apparatus in which the tee is mounted in a portable platform comprising a mass of bristles arranged to simulate an area of grass.

Other objects will be in part obvious and in part pointed out hereinafter.

In the accompanying drawings:

Fig. 1 is a perspective view showing the improved tee and supporting platform therefor.

Fig. 2 is a detail sectional elevational view taken substantially along the line II-II of Fig. 1.

Fig. 3 is a sectional elevational view taken at right angles to Fig. 2.

Fig. 4 is an elevational view showing another form of the invention.

In the illustrated embodiment of our invention, the tee 5 is mounted on a platform 6 or base which may be suitably anchored in the ground as shown. The platform may comprise a box-like receptacle 7 or chamber in which the tee 5 is placed, said receptacle having an open upper side through which a portion of the tee projects. The upper margin of the side walls 8 terminates in outwardly directed attaching flanges 9 through which the receptacle 7 is connected to a base plate 10; the latter equipped with anchoring means at one end in the form of apertured ears 11 through which pins 12 are driven. An

opening 13 in the plate 10 registers with the open upper end of the receptacle 7. A field or plot of bristles 14 carried by a plate 15 attached to the base plate 10 are suitably colored to simulate a grass area. This of course gives the apparatus a pleasing appearance and in addition cushions inaccurate strokes of the clubs when necessary. This bristle plate is also provided with a vertical opening 16 which registers with the opening 13 and upper end of the receptacle 7. A series of apertures 17 in the bottom of the receptacle 7 provide for drainage of water or the like therefrom.

The tee is so mounted that under pressure of a club in driving a ball from the tee, it will quickly move out of the path of travel of the club. Provision is also made to automatically return the tee to its original position. This may be accomplished in various ways but we have by actual practise found that pivoting a resilient tee upon a suitable support and suitably counterweighting said tee so that it always returns to a ball supporting position after a drive, is the most satisfactory arrangement.

The tee 5 comprises a seat 18 superimposed on a neck 19 rising from a body 20. The body consists for the greater part of a counterweight 21 formed of lead or similar material encased in rubber or rubber composition. The neck 19 and seat 18 may and preferably are formed of live rubber. The rubber encasing the counterweight may be similarly formed. The neck is of course highly resilient and yields readily when struck by a golf club or the like, yet quickly resumes its original position.

By providing a pivotal mounting for the tee, movement of the latter is greatly facilitated. A bearing sleeve 22 extends transversely through the upper end of the counterweight 21. A pivot pin 22-A is arranged in the sleeve 22 and has its ends journalled in bearing openings 23 in the arms 24 of a holder 25. This holder is substantially U-shape and formed with guide openings 26 in bosses 27 adapted to slidably receive guide posts 28 on a carrier 29. This carrier 29 may be attached to the bottom of the receptacle 100

7 or any other suitable base. An adjusting screw 30 provides means for regulating the elevation of the tee relative to the platform.

If while driving a ball or other object from a position on the tee, the driving club should strike the tee, the neck 19 moves forwardly in the direction of travel of the club. This forward movement of the neck is immediately followed by swinging of the entire tee about the pivot pin 22—A. Thus the tee readily moves out of the path of travel of the club and because of such movement together with the highly resilient construction of the tee, is affected very little, if any, by the blows of the clubs. As a result the tees have exceptionally long life and seldom require replacement. Furthermore, repeated setting up of tees, before a ball can be teed up is entirely unnecessary where our invention is used.

In Fig. 4 we have shown a spring 31 connecting a core member 32 in the tee with the lower end of the holder 25. This spring serves the purpose of the counterweight and allows a material shortening of the tee as a whole.

Modifications may be resorted to within the spirit and scope of the appended claims.

What we claim is:

- 30 1. In combination, a support, a golf ball tee mounted for vertical sliding and swinging movement on the support, a counterweight on the tee and means for sliding the tee and counterweight vertically and holding them at various elevations.
- 35 2. In combination, a support, a golf ball tee, a holder for the tee, pivotal connection between the tee and holder, vertical sliding connection between the holder and support and manually controlled means for adjusting the holder vertically.
- 40 3. In combination, a support, a golf ball tee, a holder for the tee, pivotal connection between the tee and holder, a counterweight yieldingly holding the tee upright in the holder, and vertical sliding connection between the holder and support.
- 45 4. In combination, a support, a golf ball tee, a substantially U-shaped holder for the tee, horizontal pivotal connection between the tee and holder, means normally yieldingly holding the tee upright in the holder, vertical sliding connection between the holder and support and manually actuated means for sliding the holder and setting it at various elevations to change the elevation of the tee while maintaining the upper end of the latter in a horizontal plane.
- 50 5. In combination, a support comprising a U-shaped frame having a pair of opposed vertical slideways open at their upper ends, a golf ball tee holder slidably supported in the slideways, a horizontal hinge pin carried by the holder, a golf ball tee pivoted

to the hinge pin, and means yieldingly holding the tee upright.

6. In combination, a support comprising a U-shaped frame having a pair of opposed vertical slideways open at their upper ends, a golf ball tee holder slidably supported in the slideways, a horizontal hinge pin carried by the holder, a golf ball tee pivoted to the hinge pin, and a counterweight forming a downward extension of the tee below the hinge pin for yieldingly holding the tee upright.

Signed at Toledo, in the county of Lucas and State of Ohio, this 8th day of January, 1930.

JOHN RALPH HOGE.
LEONARD D. SOUBIER.
